UNITED STATES PATENT OFFICE

OTTO ANDREAS ANDERSON, OF CHICAGO, ILLINOIS

DESIGN FOR A DAVENPORT OR SIMILAR ARTICLE

Application filed November 18, 1931. Serial No. 41,762. Term of patent 3½ years.

To all whom it may concern:

Be it known that I, OTTO ANDREAS ANDERSON, a citizen of the United States, residing at Chicago, in the county of Cook and State of Illinois, have invented a new, original, and ornamental Design for a Davenport or Similar Article, of which the following is a specification, reference being had to the accompanying drawings, forming a part thereof.

Fig. 1 is a perspective view of the daven-

port embodying my invention; Fig. 2 is an enlarged view of the side apron, and Fig. 3 is a partial view of the front apron showing the detail of the design in enlargement.

I claim:

The ornamental design for a davenport or similar article, as shown.

In witness whereof, I hereunto subscribe my name this 9th day of November, 1931.

OTTO ANDREAS ANDERSON
